SWIVEL CONNECTER FOR ELECTRIC WIRES

Application filed December 30, 1927. Serial No. 243,613.

The present invention relates to a connector for electric wire used in connection with electrical appliances, telephones or in other electrical connection where one end of the wire is moved about from place to place and has for an object to provide an article of this character providing a swivel connection between the various sections of the wire whereby to prevent the twisting and entangling of the same.

A further object of the invention is to provide an article of this character of simple, compact and practical construction which provides a safe means for connecting the adjacent ends of the wire without danger of causing accidental contact between the opposed wires so as to prevent short circuiting thereof, which enables the respective ends of the wire to be easily, quickly and securely attached in position thereto, which is neat and attractive in appearance, relatively inexpensive to manufacture and otherwise well adapted for the purposes for which the same is intended.

Other objects and advantages reside in the special construction and combination of the various elements comprising the invention, reference being had to the accompanying drawings forming a part hereof, wherein;

Figure 1 is a longitudinal sectional view through the connector,

Figure 2 is a transverse sectional view taken substantially along a line 2-2 of Figure 1,

Figure 3 is a perspective view of the stationary contacting collar,

Figure 4 is a similar view of the rotatably mounted connector assembly and

Figure 5 is a similar view of the threaded plug by means of which one end of the wire is attached for rotation with the rotatably assembly,

Figure 6 is a plan view of the insulating washer.

Referring now to the drawing in detail, the invention comprises a tubular, sectional connector housing composed of an intermediate section 5 internally threaded at each end for threadedly receiving end sections 6. Each of the sections 5 and 6 is formed of insulation

material, preferably porcelain, hard rubber or like non-conductive material and may be of a cylindrical formation as shown in Figure 2 or of any other desired shape and having a central bore extending longitudinally therethrough.

An annular collar 7 is arranged within the bore of the intermediate section 5, said collar having a boss 8 formed on its outer periphery with a threaded opening adapted to receive a screw 9 insertable laterally through an opening in the wall of the intermediate section whereby to secure the collar against relative movement with respect to said section. The head of the screw 9 is countersunk in a recess 10 formed in the outer surface of the intermediate section 5.

Within the collar 7 is fitted a sleeve 11 arranged for relative rotary movement therebetween. The collar 7 and sleeve 11 are constructed of conductor material adapted through their contacting relation to provide an electrical connection between the wires 12 and 13 extending through the opposite ends of the connector housing, the end of the wire 12 being attached to one end of an arm 14 by means of its screw 15, the opposite end of said arm being interposed between the boss 8 and the inner wall of the intermediate section 5 and retained in position by means of the screw 9, the end of the wire 13 being attached to an ear 16, formed on the end of the sleeve 11 and secured thereto by means of a screw 17.

The flange 18 is formed on the outer periphery of the sleeve 11 at the end thereof adjacent the ear 16 adapted to abut the edge of the collar 7 whereby to limit the inward movement of such end of the sleeve.

The socket member 19 is disposed in the sleeve 11 and retained in spaced relation from the wall of the sleeve by means of a section of insulation 20 said socket member and sleeve being assembled for rotary movement as a unit preferably by applying the porcelain thereto while in its plastic state and permitting the same to set with the parts in their assembled relation as illustrated in Figure 1 of the drawing.

The socket member 19 is provided with

a bore extending longitudinally therethrough, one end of the bore being of a relatively enlarged area as shown at 21 and internally threaded whereby to receive a threaded plug 22 having a screw 23 threadedly introduced in its outer end for attaching one end of a wire 24 to the plug. Within the reduced end of the bore of the socket member 19, opposite from the plug 22 is a pin 25 about which the 10 socket member is adapted to rotate, said pin having a head 26 formed at its inner end disposed within the enlarged portion of the bore 21 and with its opposite end extending outwardly from the socket member and to which 15 may be attached the end of a wire 27.

It is thus apparent and as will be seen from an inspection of Figure 1 of the drawings, that the pin 25 is retained within the socket member 19 and retained against rotary movement by the circuit wire 27, while the socket member may freely rotate on the pin. The end of the socket member adjacent the pin 25 is externally threaded for threadedly receiving an insulation nut 29 of sufficient diameter to overlap the boss 8 and thus coat with the flange 18 to prevent longitudinal movement of the assembly. A locking nut 30 may also be threadedly arranged on the end of the socket member 19 to prevent accidental displacement of the insulated nut 29. An insulation washer 31 is also mounted on the end of the pin 25 having a notch 32 for receiving the arm 14 and prevent possible short-circuiting of the parts. The washer is prevented from displacement from the outer end of the pin by abutting the end of the screw 28 provided for attaching the circuit wire 27 to the pin.

By arranging the parts in a manner as illustrated in Figure 1 of the drawing the opposed wires 12 and 27 of the circuit may be retained in a stationary position with respect to the connector by reason of the attachment thereof respectively to the collar 7 and pin 25 and through contact of the collar 7 with the rotatable sleeve 11 and the pin 25 with the relatively rotatable socket member 19, said wires may be attached to the wires 13 and 24 at the opposite end of the connector 50 so as to complete the circuit and at the same time provide a swivel connection between the adjacent end of the arm which will prevent the respective sections thereof from becoming twisted or entangled during the use of 55 the same.

It is obvious that the invention is susceptible of various changes and modifications, without departing from the spirit or scope of the invention or sacrificing any of its advantages, and we accordingly claim all such forms of the device to which we are entitled.

Having thus described our invention, what we claim as new is:

45 A connector of the class described comprising a tubular housing of insulation ma-

terial having a collar secured therein and an assembly rotatably mounted in the collar and providing a pair of separate conductor elements insulated from each other, one of said elements comprising a rotatable sleeve disposed within the collar in contacting relation therewith, and the other of said elements comprising a socket member concentrically arranged with respect to the sleeve and insulated from the walls thereof and having a bore 70 extending therethrough, a plug threadedly inserted in one end of the socket member, a pin extending from the opposite end thereof and about which the socket member is adapted to rotate, said plug and said pin being 80 adapted for attaching circuit wires thereto extending from opposite ends of the housing and means carried at the opposite ends of the assembly engageable with the edges of the collar whereby to prevent relative longitudinal movement therebetween.

75 85 90 In testimony whereof we affix our signatures.
